UNITED STATES PATENT OFFICE.

JAMES MOORE, OF STRATFORD, CONNECTICUT.

ENVELOP.

1,277,240.

Specification of Letters Patent. Patented Aug. 27, 1918.

Application filed October 23, 1917. Serial No. 198,090.

To all whom it may concern:

Be it known that I, JAMES MOORE, a citizen of the United States, and a resident of Stratford, in the county of Fairfield and 5 State of Connecticut, have invented a new and Improved Envelop, of which the following is a full, clear, and exact description.

My invention relates to an envelop of the safety type which is characterized by the 10 provision of tongues extending from the covering flap and for which slots are provided in the other flaps of the envelop, said tongues being provided with adhesive adapted to engage the side flaps of the 15 envelop and retain the same in position when the envelop is sealed.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views.

Figure 1 is a plan of the blank;

Fig. 2 is the blank partly folded in the envelop;

30 Fig. 3 is the elevation of the envelop closed; and

Fig. 4 is a fragmentary section on line 4—4, Fig. 3.

Referring to the drawings, the blank is 35 cut in the manner customary for an ordinary envelop. It has a main section 5, bottom flap 6, side flaps 7, and covering flap 8. The covering flap has closing or locking tongues 9 which are disposed at a distance 40 from the apex so that their edges 10 nearer to the apex are adapted to coincide with the lower edges 11 of the side flaps 7. The width of the tongues 9 is substantially equal to the width of the overlap 12 formed by 45 the bottom and side flaps when the envelop is folded (see Fig. 3). The locking tongues 9 preferably taper toward their free end and are cut at such an angle on the covering flap as to coincide with the obliquity of the over- 50 lap formed by the bottom and side flaps.

The edges 11 of the side flaps 7 have notches 13 with which slots 14 in the bottom flap 6 are adapted to coincide when the envelop is folded (see Figs. 2 and 3). These

slots and notches when in register are 55 adapted to receive the corresponding locking tongues 9. These tongues will lock the flaps together when said tongues are folded inwardly against the inner surface of the side flaps 7 after the tongues have been 60 passed through the slots and notches.

To prevent the side flaps 7 from being pulled out sidewise, intentionally or otherwise, and to insure against accidental injury to the tongues 9, the edge of the covering tongue is provided with adhesive. In consequence if any unauthorized person tries to disengage the covering flap from its engagement with the rest of the envelop, it will be necessary to rupture the tongues 9 and, 70 therefore, the tampering with the envelop will be apparent.

I claim:

1. An envelop of the class described comprising a blank having a bottom flap, side flaps, a covering flap, and locking tongues 75 extending from the edges of the covering flap so as to follow the obliquity of the overlapping edges of the bottom and side flaps when said covering flap is folded over said bottom and side flaps, said side flaps having notches and said bottom flap having slots adapted to register with said notches when 80 said bottom flap is folded over said side flaps, said tongues being adapted to engage 85 the registering notches and slots and lock the flaps together.

2. An envelop of the class described comprising a blank having a bottom flap, side flaps, a covering flap, and locking tongues 90 extending from the edges of the covering flap so as to follow the obliquity of the overlapping edges of the bottom and side flaps when said covering flap is folded over said bottom and side flaps, said side flaps having notches and said bottom flap having slots adapted to register with said notches when 95 said bottom flap is folded over said side flaps, said tongues and edge of the covering flap being gummed, said tongues being 100 adapted to engage the registering notches and slots, the gum on said tongues preventing the unlocking of said side flaps by a side pull, the gummed portion of the covering flap preventing accidental damage to said 105 tongues when engaged by the notches and slots of the bottom and side flaps.

JAMES MOORE.
